DELIVERY DEVICE

Percy C. Smith, Chicago, Ill., assignor to John F. Meyer, Flintridge, Calif.

Application September 30, 1933, Serial No. 691,633

2 Claims. (Cl. 221—146)

This invention relates to delivery devices of the kind adapted for use in vending and amusement machines wherein articles of merchandise or prizes are delivered to the operator from the machine.

Articles of merchandise or prizes are usually displayed on an enclosed table or platform in vending and amusement machines and are removed therefrom to be passed out of the machine and it is desirable to prevent removal of the articles or prizes otherwise than by normal and proper functioning of the machine. Moreover, it is desirable to so deliver the articles that the operator of the machine need not be alert to prevent a delivered article from falling onto the floor or being otherwise damaged in the delivery thereof. Hence, important objects of my invention are to prevent surreptitious removal of displayed and dispensable articles or prizes from a vending or amusement machine and to entrap delivered articles so that they may be removed from the delivery device at leisure.

Further objects are to so mount the delivery device that it may be moved between article receiving and article delivery positions at the will of the operator; to prevent passage of articles into the delivery device when it is in delivery position and thereby close off access to the article storage space; to limit movement of the delivery device to thereby accurately position it in its alternate positions; to provide an article receiving pocket in the delivery device and a single opening affording access to the pocket and to so locate the opening that it is aligned with the article delivery chute of the machine when the delivery device is in article receiving position and so that the opening is in accessible position when the delivery device is in delivery position; to so form the pocket that articles may be expeditiously removed therefrom; and to provide a delivery device of simple and economical manufacture and adaptable for use in amusement and vending machines of different construction.

In the selected embodiment of the invention illustrated in the accompanying drawing

Fig. 1 is a fragmentary vertical sectional view of an amusement and vending machine in which my novel delivery device is mounted;

Fig. 2 is a sectional detail view taken substantially on the line 2—2 on Fig. 1; and

Fig. 3 is a sectional detail view taken substantially on the line 3—3 on Fig. 1 and showing my delivery device in delivery position.

My novel delivery device, as illustrated in the accompanying drawing, includes a wall 4 bent

into substantially semi-circular outline. A plate 5 depends from the upper end of the wall 4 and extends substantially radially of the semi-circular outline of the wall and terminates substantially at the center about which the wall is bent. An inclined wall 6 extends from substantially the medial part of the plate 5 inwardly toward the lower part of the wall 4 and includes an inwardly curved part 7 which merges into the wall 4 in spaced relation with the lower end thereof, thereby defining an extension 8 of the wall 4. The coextensive parts of the plate 5 and wall 6 are joined by a web 9 in which trunnions 10 are fast to provide pivots about which the delivery device may be rotated. Plates 11 are fast to the side edges of the wall 4, plate 5 and wall 6 and cooperate therewith to provide a pocket 12. In order to limit the size of the pocket and thereby confine articles therein so as to be readily accessible, a wall 13 is provided which extends between the wall 4 and the plate 5 in spaced relation with the juncture thereof and the wall 13 and the curved part 7 of the wall 6 free the pocket 12 of small recesses in which small articles might be trapped and render removal thereof difficult. An opening 14 is provided in the wall 4, which is located in a manner to be described. A handle 15 is provided on the face of the plate 5, and this handle may be grasped to enable pivoting of the delivery device about the trunnions 10.

Herein I have illustrated my novel delivery device in a vending and amusement machine of the kind shown in the patent to John F. Meyer, No. 1,927,877, patented September 26, 1933. The illustrated machine includes a vertical front wall 16 and a horizontal table or platform 17 enclosed by the front and other walls of the machine. That part of the front wall 16 above the table 17 is equipped with a glass panel 18 so that dispensable articles mounted on the table 17 may be viewed by the operator of the machine. An opening is provided in the front wall 16 below the table 17 and a frame 19 is mounted in this opening. The frame 19 encloses an opening of a size substantially equal to the size of the plate 5 so that said plate 5 closes the opening within the frame 19 when the trunnions 10 are journaled in the frame 19 to mount my novel delivery device in the vending machine.

An opening is provided in the table 17 and a delivery chute 20 is mounted in this opening and includes a funnel-shaped delivery part 21 which has an open lower end that is curved complementary to the wall 4. The opening 14 is so located in the wall 4 that when the plate 5 is in position

to close the opening in the frame 19 the opening 14 is aligned with the open lower end of the delivery part 21 of the chute 20.

The illustrated machine includes a pickup device 22 that picks up articles from the table 17 and carries them to the delivery chute 20, and when the pickup device 22 is opened the picked up articles fall into the delivery chute 20 and pass through the delivery part 21 thereof and the opening 14 into the pocket 12. The extension 8 abuts a pad 23 mounted on the inner side of the front wall 16 to retain the delivery device in position whereat the opening 14 is aligned with the open lower end of the delivery part 21.

After an article has been delivered into the pocket 12, the handle 15 is grasped and the delivery device is turned about the trunnions 10 into the broken line position of Fig. 1. The opening 14 is so located that when the delivery device is so pivoted this opening is disposed beyond the front of the wall 16 and therefore the operator may reach in through the opening and remove an article which has been delivered into the pocket 12. In order to limit the forward movement of the delivery device, a bumper 24 is provided on the side of the delivery device and when the delivery device has been pivoted sufficiently to disclose the opening 14, this bumper abuts the frame 19 and limits further forward movement.

When the delivery device is in article receiving or closed position, the plate 5 closes the opening in the frame 19 and prevents access to the articles on the table 17. When the delivery device is in delivery position, that is to say, when the opening 14 is disposed beyond the front of the wall 16 that part of the wall 4 behind the opening 14 closes the open lower end of the delivery part 21 of the delivery chute and therefore access to the table 17 is prevented. In fact, access to the articles on the table 17 is prevented at all times for the extent of the wall 4 between the wall 16 and the front edge of the opening 14 and the width of the opening 14 is such that prior to the time any part of the opening 14 is disclosed beyond the front of the wall 16, the rear end of the opening 14 is past the open lower end of the delivery chute 21.

I have illustrated a preferred form of my invention but it is to be understood that the delivery chute might be mounted in a machine other than that which I have described and furthermore I do not wish to be limited to the precise details set forth but desire to avail myself of such changes and alterations as fall within the purview of the following claims:

I claim:

1. In a delivery device for use in a vending or amusement machine having a delivery opening in one wall thereof and a delivery chute therein

spaced from said opening, a body providing a pocket, a part on said body and normally closing the delivery opening, means pivotally supporting the body in the machine whereby said body may be pivoted to move said part from closing position relative to the delivery opening, said body having an opening therein aligned with the delivery chute when said part is positioned to close said delivery opening, a protective wall on said body extending between said part and the edge of the opening in the body nearest to said part, a wall on said body extending from the edge of the opening therein most remote from and forming a part of the closure for said pocket, and means to facilitate pivotal movement of said body whereby when said body is pivoted to move said part from closing position relative to said delivery opening, the opening in said body moves from alignment with the delivery chute and said protective wall closes off the delivery chute until the opening in said body is out of alignment with the delivery chute whereupon the wall forming a part of the closure for said pocket closes off the delivery chute.

2. In a delivery device for use in a vending or amusement machine having a delivery opening in one wall thereof and a delivery chute therein spaced from said opening, a body providing a pocket, a part on said body and normally closing the delivery opening, means pivotally supporting the body in the machine whereby said body may be pivoted to move said part from closing position relative to the delivery opening, said body having an opening therein aligned with the delivery chute when said part is positioned to close said delivery opening, a protective wall on said body extending between said part and the edge of the opening in the body nearest to said part, a wall on said body extending from the edge of the opening therein most remote from and forming a part of the closure for said pocket, means to facilitate pivotal movement of said body whereby when said body is pivoted to move said part from closing position relative to said delivery opening, the opening in said body moves from alignment with the delivery chute and said protective wall closes off the delivery chute until the opening in said body is out of alignment with the delivery chute whereupon the wall forming a part of the closure for said pocket closes off the delivery chute.
